DESIGN FOR A DRESS

Theresa Fritz, Hoboken, N. J.

Application February 11, 1938, Serial No. 75,083

Term of patent 3½ years

To all whom it may concern:

Be it known that I, Theresa Fritz, a citizen of the United States of America, residing in city of Hoboken, county of Hudson, and State of New Jersey, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

My design is characterized by the specific embroidery on the front, back, and sleeve portions of the dress as shown.

I claim:

The ornamental design for a dress substantially as shown and described.

THERESA FRITZ.
